UNITED STATES PATENT OFFICE

2,450,700

OIL REFILLING DEVICE

Cecil Gordon Vokes and Arthur Henry Fowler,
Guildford, England, assignors to Vokes Limited,
Guildford, Surrey, England

Application August 2, 1944, Serial No. 547,749
In Great Britain June 15, 1943

3 Claims. (Cl. 184—105)

1

It is often considered desirable to incorporate a filter in the filling system for the oil sump or reservoir of an internal combustion engine; but the oil may be viscous and cold and it is difficult to get it through efficient filtering means within a reasonable time under ordinary pressure.

The main idea underlying the present invention is to provide a large area for the filtering screen with a container above it of sufficient capacity to hold the normal filling charge.

As applied to an internal combustion engine, the container may be placed in a position where its contents will be heated by the engine, and in this way the oil becomes warmed and gradually passes through the filter and into the lubrication system as the engine is running.

The invention is illustrated in typical form by the accompanying drawings, the parts of the invention for which a monopoly is desired being those delimited by the claims.

In the drawings—

Fig. 1 is a side view showing the general arrangement of a preferred form of the invention as applied to an engine with overhead valve gear.

Fig. 2 shows an alternative arrangement as applied to an engine with crank-case oil filling.

Fig. 3 is a sectional elevation to a larger scale of the filler portion of Fig. 1, and

Fig. 4 is a central cross section of Fig. 3.

In the form of the invention as applied to engines with overhead valve gear (Fig. 1), the casting 1, 1a is placed over the valve gear and may form the sole cover therefor or may do so in conjunction with the normal cover 2, discharging into a filling aperture 3 provided therein. The container 1 has an elongated dome-like cover 1a and is provided with a deeply crimped or pleated fabric and wire gauze filtering screen 4 suitably supported over the valve gear enclosed by the normal cover 2. The support may be afforded as shown in Figs. 3 and 4 by cross bars of an inner framing 5 and a coarse wire gauze 6. Supporting brackets 7 are secured under the container 1 and are bolted to the normal valve mechanism cover 2 by the same studs 8 and nuts 9 that secure the cover 2. A filler hole and cap 10 may be provided at the top or slightly to one side of the cover 1a as may be most convenient. The capacity of the container 1 over the filter 4 is sufficient to take the normal re-fill of lubricating oil—possibly from a pint upwards for ordinary car engines. The desired quantity is then simply poured in over the filter and the cap 10 replaced. As the oil warms up it will pass through the filter and find

2

its way into the return flow from the valve gear to the sump or reservoir.

In the form shown at Fig. 2 the arrangement is generally similar to Figs. 3 and 4, but the container 1 is secured in a suitable position against the back of the dash of a car and a flexible pipe 11 from the lowest point of the container 1 is suitably secured to the ordinary crank case oil filler cap 12.

10 While described with more particular reference to internal combustion engines, like purposes to which the invention is applicable would include other cases where oil is carried in a service tank or reservoir (as on aircraft, gun turrets and many other instances) from which oil is drawn and to which it is returned and the tank is topped up from time to time by a filling charge.

We claim:

1. A lubricating means for supplying oil to an engine to build up the volume of engine-carried oil to a desired quantity, including a container to receive a build-up oil charge, means for connecting the container to the engine to cause the heat developed in the engine to heat the charge in the container, a communication between the container and engine for oil passage, and a filter in the container of a character to prevent filter passage of the conventional viscous oil delivered and afford such filter-passage following the heating of 30 the oil in the container.

2. A means for delivering a build-up charge of oil to the oil body of an engine, said means comprising a container to which the build-up charge is delivered in normal condition, a discharge passage for delivering oil from the container to the engine, the container being connected to the engine to utilize the heat of the engine to materially increase the interior temperature of the interior of the container to reduce the viscosity of the oil originally delivered to the container, and a filter 35 between the discharge passage and main body of the container serving to prevent oil passage to the discharge passage in its normal viscous condition and afford such passage together with the filtering function following sufficient heat from the engine, properly reducing such viscosity.

3. A construction as defined in claim 1, wherein a frame is fitted within the container to receive and support the filter, and means forming part of 40 the engine assembly for removably engaging said frame.

CECIL GORDON VOKES,
ARTHUR HENRY FOWLER.
